Primary Examiner — T. Chase Nelson*Assistant Examiner* — Deanna Fluegeman(74) *Attorney, Agent, or Firm* — Apex Juris, pllc; Tracy M Heims(57) **CLAIM**

The ornamental design for a pattern applied to a computer, as shown and described.

DESCRIPTION

FIG. 1 is a front view of a first embodiment of a computer with applied pattern according to my new design;

FIG. 2 is a front side perspective view of a second embodiment thereof;

FIG. 3 is a front side perspective view of a third embodiment thereof;

FIG. 4 is a front side perspective view of a fourth embodiment thereof;

FIG. 5 is a front side perspective view of a fifth embodiment thereof;

FIG. 6 is a front view of a sixth embodiment thereof;

FIG. 7 is a front view of a seventh embodiment thereof;

FIG. 8 is a front view of an eighth embodiment thereof; and, FIG. 9 is a front view of a ninth embodiment thereof.

The broken line showing of the computer is included for the purpose of illustrating unclaimed environmental structure and forms no part of the claimed design.
